[57] ABSTRACT

The device firmly secures a spring winder means to a spring winding stem by means of a coil spring intimately fitted over the spring winder means and the spring winding stem threadably connected together. The convolutions of the coil spring are directed in the same direction as the threads formed in the spring winder means and spring winding stem for threadable connection, so that the coil spring is tightened if the spring winder means is turned in a direction in which it is threadably disconnected from the spring winding stem. Thus, the spring winder means is firmly secured to the spring winding shaft through the coil spring and prevented from being dislodged therefrom.

6 Claims, 3 Drawing Figures

FIG. 1

FIG. 2

FIG. 3

DEVICE FOR FIXING SPRING WINDER MEANS

Background of the Invention

This invention relates to a device for fixing a winder means for springs or the like.

Generally, a key for winding a spring, or other means for performing the same function as the key are detachably connected, as by threading, to a spring winding stem attached to the spring, so that the key can freely be connected to or disconnected from the spring winding stem.

When the spring winder means is detachable from the spring winding stem, it is likely to be lost or misplaced. When such detachable spring winder means is used with a clockwork toy for children, there is the hazard of a small child putting it in the mouth, while playing, and swallowing it.

It is desirable therefore that the spring winder means be constructed such that it cannot readily be disconnected from the spring winding stem once it is connected thereto.

In firmly securing the spring winder means to the spring winding stem, the threadable connection of the spring winder means and the spring winding stem may be crushed by crimping it with pliers, or the former may be joined by soldering to the latter. If the spring winder means were firmly secured to the spring winding stem of a toy in this way, it would be impossible to disconnect them till the toy is broken and discarded. Thus, when it is desired to repair the toy, it would be impossible to disassemble it into its component parts.

Summary of the Invention

This invention has as its object the provision of a device for fixing spring winder means comprising a spring winding stem having a threaded portion, a spring winder means having a threaded portion adapted to be threadably connected to the threaded portion of the spring winding stem, and a coil spring adapted to be fitted intimately over the spring winding stem and the spring winder means, threadably connected together, the coil spring comprising convolutions arranged in a direction which is the same as the direction in which the threads formed on the spring winding stem and the spring winder means for threadably connecting them together are wound, so that the spring winder means threadably connected to the spring winding stem can be firmly secured thereto by means of the coil spring and cannot readily be disconnected therefrom by turning the spring winder means in any direction once it is fixed to the spring winding shaft.

The device according to this invention is very simple in construction and yet positive in performing the operation of firmly securing the spring winder means to the spring winding stem and preventing it from being disconnected. The coil spring mounted between the spring winder means and the spring winding stem ensures that the winder means is not disconnected from the winding stem once the former is threadably connected to the latter.

According to this invention, the spring winder means is not permanently connected to the spring winding stem, but the former can be disconnected from the latter when desired. That is, if the spring winder means is unscrewed after the coil spring is loosened, the spring winder means can be readily disconnected from the spring winding stem. This arrangement facilitates re-

pair and disassembling. Loosening of the coil spring should require a considerably high force, so that the winder means is prevented from being inadvertently dislodged or removed by a child.

Other and additional objects as well as features and advantages of the invention will become evident from the description set forth hereinafter when considered in conjunction with the accompanying drawings.

Brief Description of the Drawings

FIG. 1 is a plan view, with certain parts being broken away, of the device for fixing spring winder means comprising one embodiment of this invention, showing the spring winder means having the coil spring mounted over it being juxtaposed to the spring winding stem;

FIG. 2 is a plan view, with certain parts being broken away, of the device according to this invention, showing the spring winder means having the coil spring mounted over it being threadably connected to the spring winding stem; and

FIG. 3 is a fragmentary plan view, on an enlarged scale, of FIG. 2.

Description of a Preferred Embodiment

The invention will now be described with reference to an embodiment in which the spring winder means is a key provided with an internal threaded portion and the spring winding stem is provided with an external threaded portion. It is to be understood that the invention is not limited to this embodiment and that an internal threaded portion may be provided in the spring winding stem and an external threaded portion may be provided in the spring winder means. The spring winding stem may be a shaft having one end to which a spring is attached, or may be a spring shaft itself.

In FIG. 1, a spring winding stem 1 having a spring 4 attached to one end portion thereof is supported by a frame 3 such as of a toy, and the other end portion of spring winding stem 1 is provided with an external threaded portion 2.

On the other hand, a spring winder means or key 5 adapted to be connected to spring winding stem 1 is provided at a forward end portion thereof with an internal threaded portion 6 adapted to threadably engage the external threaded portion 2 of the spring winding stem 1.

The key 5 is formed on the outer circumferential surface thereof with an offset portion 9 to provide a minor diameter portion 7 at the end portion of key 5 which has an outer diameter substantially the same as the outer diameter of spring winding stem 1. A coil spring 8, having convolutions directed in the same direction as the thread of the threaded portion on the key 5 is lightly force fitted over the minor diameter portion 7 of key 5 at one end portion thereof, and then the key 5 is threadably connected to the spring winding stem 1 so that the other end portion of coil spring 8 is lightly force fitted over the outer circumferential surface of spring winding stem 1 as shown in FIG. 2. Preferably, the coil spring 8 has an inner diameter which is equal to or smaller than the outer diameter of the minor diameter portion of key 5. The coil spring 8 may be constructed such that its inner peripheral surface partly engages winding stem 1 and key 5.

If one tries to turn the key 5 in the direction of an arrow as shown in FIG. 3 in an effort to disconnect the key 5 from the spring winding stem 1 by unscrewing

after the coil spring 8 is force fitted over the threadably connected key 5 and stem 1, the key 5 and stem 1 will be locked by the coil spring 8 since the frictional force imparted to the coil spring 8 when it is force fitted over the minor diameter portion of key 5 acts on the coil spring 8 to force it tightly over the stem 1 by virtue of the arrangement in which the convolutions of coil spring 8 are directed in the same direction as the thread formed on the key 5. It is thus impossible to disconnect the key 5 from the winding stem 1 by unscrewing. Also, the frictional force imparted to the coil spring 8 when it is force fitted over the spring winding stem 1 in threadably connecting the key 5 to the stem 1 acts to loosen the coil spring 8, thereby enabling the key 5 and stem 1 to be maintained in threadable connection.

The coil spring 8 is precluded from axial movement by abutment against the offset portion 9 and against the frame 3 to which the spring winding stem 1 is connected, the offset portion 9 having a height which is greater than or equal to the diameter a of a wire constituting the spring. Thus, end portions of the coil spring are not exposed and the hazards of the hands of a child being injured by them are precluded. It is to be understood that the offset portion can be provided on the outer circumferential surface of the spring winding shaft 1, not on the outer circumferential surface of the key 5 as aforementioned.

According to this invention, the portion of the coil spring 8 which extends outwardly beyond the end of the minor diameter portion 7 of key 5 over which the coil spring 8 is force fitted has a length b which is smaller than the length of the external threaded portion 2 of the spring winding stem 1. By this arrangement, the force fitting of the coil spring 8 over the spring winding stem 1 can be initiated while the spring winding stem 1 is still in the process of being screwed into the key 5. This expands the coil spring 8 and thereby facilitates the screwing of the spring winding stem 1 into the key 5.

When the inner diameter of coil spring 8 is much smaller than the outer diameter of spring winding stem 1, the force fitting of coil spring 8 over the spring winding stem 1 will be facilitated if the portion of the coil spring 8 disposed on the side of spring winding stem 1 is expanded to have a greater inner diameter or if the end of the stem 1 from which the external threaded portion 2 extends is cut aslant to provide a shoulder 1a therein.

What I claim is:

1. A device for fixing spring winder means comprising

50

ing a spring winding stem formed with a threaded portion, a spring winder means formed with a threaded portion and adapted to be threadably connected to said spring winding stem, one of said threaded portions being a male threaded stud and the other of said threaded portions being a female threaded socket portion for receiving said threaded stud; and a cylindrical coil spring intimately fitted around non-threaded portions of said spring winding stem and said spring winder means when said stem and said winder means are threadably connected to each other, said coil spring being wound in a direction which is the same as the direction in which the threads of the threaded portions, formed on the spring winding stem and the spring winder means extend for threadably connecting them together.

2. A device for fixing spring winder means as set forth in claim 1 wherein said spring winder means is formed with a minor diameter portion over which said coil spring is adapted to be fitted, said minor diameter portion of said spring winder means having an outer diameter which is substantially the same as the outer diameter of a portion of said spring winding stem which has no thread thereon, said coil spring having an inner diameter which is equal to or smaller than the outer diameter of said minor diameter portion of said spring winder means.

3. A device for fixing spring winder means as set forth in claim 1 wherein at least one of said spring winder means and said spring winding stem is formed with an offset portion of a height greater than the diameter of a wire constituting said coil spring.

4. A device for fixing spring winder means as set forth in claim 1 wherein the threaded portion of said spring winder means is an external threaded portion and the threaded portion of said spring winding stem is an internal threaded portion.

5. A device for fixing spring winder means as set forth in claim 1 wherein the threaded portion of said spring winder means is an internal threaded portion and the threaded portion of said spring winding stem is an external threaded portion.

6. A device for fixing spring winder means as set forth in claim 5, wherein a portion of said coil spring extending outwardly from the end of said minor diameter portion of said spring winder means, over which said coil spring is fitted, has a length which is smaller than the length of said external threaded portion of said spring winding stem.
